SINGLE CIRCUIT ELECTRICAL HOUSING

John Hammond Geis, Jr., and Robert La Rue Williamson,
Harrisburg, Pa., assignors to Amp Incorporated, Harris-
burg, Pa.

Filed June 10, 1965, Ser. No. 85,668

Term of patent 14 years

(Cl. D26—1)

FIGURE 1 is an exploded, perspective view of a single circuit electrical housing showing our new design;
FIGURE 2 is a similar view taken from the opposite end;

FIGURE 3 is a side elevational view of the parts in an assembled position;

FIGURE 4 is an elevational view taken from the left of FIGURE 3; and

FIGURE 5 is an elevational view taken from the right of FIGURE 3.

We claim:

The ornamental design for a single circuit electrical housing, as shown.
